CLAIM

The ornamental design for a combined ceiling fan motor housing, brackets and light fixture unit, as shown and described.

DESCRIPTION

FIG. 1 is a front-left-bottom perspective view of a combined ceiling fan motor housing, brackets and light fixture unit showing my new design;

FIG. 2 is an enlarged front elevational view thereof;

FIG. 3 is an enlarged rear elevational view thereof;

FIG. 4 is an enlarged left side view thereof;

FIG. 5 is an enlarged right side view thereof;

FIG. 6 is an enlarged top plan view thereof;

FIG. 7 is an enlarged bottom plan view thereof; and,

FIG. 8 is a front-left bottom perspective view thereof, the broken line showing of environmental structure being for illustrative purposes only, and forms no part of the claimed design.
